APPARATUS FOR MAKING SPOOL-ENCLOSING SHELLS

John A. Johnson, Woodhaven, N. Y.

Application June 27, 1936, Serial No. 87,717

20 Claims. (Cl. 113—1)

This invention relates to apparatus for making shells to be engaged upon the flanges of spools, usually of circular form, carrying a strand or web of material, such as adhesive medicated tape, wound upon the core of the spool, said shell being adapted to enclose the space between the spool flanges and in conjunction with the spool flanges form an enclosing casing for the material wound upon the spool core. It is an object of the invention to provide improved apparatus for efficiently and expeditiously making shells of this character.

Shells for this purpose comprise a sheet metal body of cylindrical or barrel form of slightly greater length than the spool and are provided with a rolled bead at each end to reinforce the body by rolling the material at the ends of the body upon itself. To releasably retain the spool within the shell or casing, the body of the shell is provided with nibs or protuberances extending inwardly and spaced about the body at each end. Said nibs or protuberances are pressed from the material of the body and arranged to engage within and at the inner side of the peripheral portion of the spool flanges, and over which nibs or protuberances the peripheral portion of the spool flanges is adapted to be sprung in engaging the spool in and removing it from the shell or casing.

It is a further object of the invention to provide improved apparatus for providing the body of the shell or casing with a reinforcing bead at each end and in successive sequence therewith press portions of the material of the body inwardly to form the body with nibs or protuberances spaced about and arranged adjacent the ends of the body of the shell.

Apparatus of this character is adapted for use in connection with machines for making cylindrical bodies or barrels, such as container bodies, comprising means to shape a blank to cylindrical form about a horn and secure it at the longitudinal marginal portions to retain it in said condition. The body or barrel so formed in said machine is transferred from said machine to the apparatus of the present invention for curling the opposite end portions of the body or barrel and provide the same with inwardly extending nibs or protuberances adjacent the opposite ends and circumferentially spaced about the same. In order that the body or barrel will be delivered from the forming machine therefor to a horizontal support or horn therefor arranged centrally of a die of a head, it is essential that

such horn or support be in alignment with the horn of the body or barrel forming machine.

It is a further object of the invention to provide in apparatus of this character a frame for supporting the operative parts and a base upon which the frame is mounted to have adjustment in a vertical direction together with means for effecting such adjustment of the supporting frame.

In the drawings accompanying and forming a part of this application Figure 1 is a plan view of apparatus embodying the invention.

Figure 2 is a sectional view taken substantially on the line 2—2 of Figure 1 looking in the direction of the arrows.

Figure 3 is an end elevation, partly in section, the section being taken substantially on the line 3—3 of Figure 1 looking in the direction of the arrows.

Figure 4 is a side elevation, partly in section, of the means for arranging the body shell with inwardly extending nibs or protuberances.

Figure 5 is a front elevation of the means for arranging the shell body with inwardly extending nibs or protuberances and viewed from the left of Figure 4 with the parts shown in operative position.

Figure 6 is a view similar to Figure 5 with portions thereof broken away but showing the parts in normal inoperative position.

Figure 7 is a sectional view of the product of the apparatus showing the manner of retaining a spool within the shell by the inwardly extending nibs or protuberances; and

Figure 8 is a perspective view of a portion of the framework for supporting the operative parts of the apparatus and mounting base therefor together with means for adjusting the frame vertically of the base.

As stated it is an object of the invention to provide an apparatus for making shells to co-operate with the flanges of spools to enclose material wound upon the core of the spool between the spool flanges, as shown in Figure 7, wherein a spool S is shown engaged within a shell comprising a body B of cylindrical form provided at the opposite ends with reinforcing beads by rolling or curling the edge portions of the body outwardly upon themselves, as at 9. The enclosing shell is of somewhat greater length than the spool, and the shell is provided adjacent the ends with inwardly extending nibs or protuberances 10 to engage at the outer side of the spool flanges and releasably retain the spool within the shell, said nibs or protuberances being formed by pressing portions of the material of the shell inwardly.

In engaging the shell upon the spool, the spool is tilted slightly to engage a peripheral portion of a spool flange within certain of the nibs 10 when the opposite peripheral portion of the spool flange is pressed inward to spring the shell and spool flange sufficiently to cause said opposite peripheral portion of the flange to pass over the adjacent nib. The spool is removed from within the shell by exerting a pressure on a spool flange to cause the same to be sprung from within the shell.

In the embodiment of the apparatus illustrated for carrying out the invention, the operative parts are mounted upon a frame F including standards 15 A mounted on a base C, and upon an auxiliary frame support D carried by an auxiliary base E for a horizontal portion of the frame.

A series of supports 11 for the shell body B are 20 removably and interchangeably mounted in a head 12 of a turret 13 mounted in the frame F to rotate on a vertical axis, the supports extending laterally from the turret head at substantially a right angle to the axis of said head, there being four of said supports 11 in the present instance spaced 90 degrees apart about the turret head. To mount the supports 11 in the turret head, they are provided with a reduced portion at one end which is engaged in a bore in the turret head 12, as shown in Figure 3; and to permit of axial adjustment of the supports 11, they are provided with a screw threaded portion engaged by a threaded collar, as at 14, held to the turret head 12 by clamping members releasably secured to the turret head by screws, as shown 25 at 15. The supports 11 are locked in adjusted position by set screws 16 threaded into bores extended into the top of the turret head abutting the reduced portion of the supports engaged in the turret bores. The supports 11 are in the 30 nature of dies to effect the curling or rolling outwardly and inwardly of the marginal portion at one end of the shell body B to provide it with the reinforcing bead at said end. For this purpose, the supports are provided with a portion, which 35 is in the nature of a horn or support proper for the shell body B, having a diameter substantially the same as the diameter of the shell body B. Said horn extends forwardly of an annular portion 11' of enlarged diameter at the juncture 40 of the horn with the reduced portion of the support. The annular enlarged portion 11' has in the face thereof at the juncture of the horn, a recess of semicircular form in cross section, as at 11', whereby, as an endwise thrust is applied 45 to the shell body on the horn the marginal end portion engaging said face will be caused to be rolled outwardly and inwardly upon itself and provide the shell body B with the bead 9 at one end.

The turret is intermittently rotated to successively position the supports or horns at stations a, b, c and d. In position a, the horns are adapted to receive a shell body B thereon, which may be received directly from the horn e (Figure 2) of a 50 container body forming machine about which the shell body is formed and delivered from said horn e onto the support or horn 11 of the turret by feeding means at opposite sides and reciprocatory longitudinally of the horn e, as shown in a conventional manner at f. The turret horn 11 with the shell body thereon is then positioned at station b, where no operation is effected on the shell body B. Upon the next movement of the turret head 12, the turret horn 11 is positioned at station c relative to means in the nature of a die 55

47 complementary to the die 11' of the horns 11, adapted to engage the shell body on the turret horn 9 stationed relative thereto, and operative to exert a force upon the shell body to thrust the one end against the wall of the semicircular recess in the enlarged portion 11' of the turret horn 11 and roll said end of the shell body outwardly and inwardly. The complementary die also has an annular recess 48 of semicircular form in cross section, which simultaneously rolls the opposite end of the shell body outwardly and inwardly upon itself, and thus, forming the reinforcing beads 9 at the opposite ends of the shell body. Upon the next movement of the turret, the turret horns are positioned at station d, and means are arranged at said station to provide the shell body with the inwardly extending nibs or protuberances 10 and remove the shell body from the turret horn 11.

The present apparatus is adapted for use in connection with container body forming apparatus with the horn, about which the body is formed, of such apparatus being in alinement with a turret horn 11 at station a, and the present apparatus is operatively connected with the 20 container body forming apparatus to operate both apparatus in synchronism. In the present instance, the apparatus is shown as independently operative and operated from a suitable source of power, the apparatus being shown as provided with a pulley 17 loose on a drive shaft 18 and adapted to be coupled to the shaft through a clutch, shown in a conventional manner at 19 (Figure 1). The turret is intermittently rotated from the drive shaft 18 through a Geneva gear 30 operatively connected with the drive shaft 18, one member 20 of said gear being fixed to a shaft 21 operatively connected with the turret by a bevel gear 22 fixed on the shaft 21 meshing with a bevel gear 23 fixed to the turret 13. The 35 member 20 is driven from a wheel 24 fixed on a shaft 25 driven from the drive shaft 18 by a bevel gear 26 on shaft 25 meshing with a bevel pinion 27 on a shaft 28 having a bevel gear connection 29 with shaft 18. The Geneva gear is 40 arranged to transmit two intermittent movements to the turret upon each revolution of the shaft 25. For this purpose, the member 20 in the form of a wheel is provided with four slots 30 extended radially inward of the wheel and equidistantly 45 spaced about the same, the peripheral portions of the wheel 20 between the slots being arranged of convex form, as at 31. The wheel 24 carries a pair of rollers mounted on diametrically opposite studs fixed in and extending from a face of the wheel, as at 32, said rollers upon each one-half revolution of the wheel 24 being adapted to successively engage successive slots in the wheel 20. A member 33 having diametrically opposite convex portions 34 is rotatable with the wheel 24 and one of which convex portions is adapted to engage and travel relative to a concave portion 31 of the wheel 20 and hold said wheel, and thereby, the turret against movement during the 50 periods of rest of said wheel 20.

To positively lock the turret against movement during the periods of rest, the turret head 12 is provided with a series of recesses 36, these recesses being four in number, equal in number to and arranged in axial alinement with the supports 70 11, and adapted to be engaged by a detent 35. The detent 35 is mounted to have sliding movement toward and away from the turret head, in the present instance in alinement with a horn or support 11 in the shell body receiving position a 75

thereof. As shown, the detent 35 is mounted in a slideway 37 in a bracket 38 fixed to the frame F and urged toward the turret head to engage a notch or recess 36 therein by a spring 39. The 5 detent is moved out of engagement with a turret recess 36 just prior to transmitting intermittent movement to the turret by a lever 40 pivotally carried by arms 38' extended from the bracket 38, one arm of the lever being bifurcated for the passage of a rod 41 fixed at one end to the detent, and said lever arm adapted to engage an abutment 42 adjustably mounted on the rod at the outer side of the bifurcated end of the lever arm when actuated to move the detent against the action of the spring 39. The lever is actuated to release the detent from a turret recess by a roller 43 rotatably carried in a bifurcation at the end of the other lever arm following a cam 44 fixed on a shaft 45 having a bevel gear drive connection 46 20 with the shaft 28, the cam being arranged to actuate the lever in timed sequence with the actuation of the turret to move the locking detent 35 out of a turret recess 36 and release the detent to permit it to assume locking position.

25 After a shell body B has been engaged at station a upon a turret horn or support 11, the turret 13 is advanced to position b where no operation is effected upon a shell body on the support therefor at said station; but a shell body B is engaged upon a successive horn or support 11 at station a. In the successive movement of the turret 13, the turret horn 11 is positioned at station c relative to the means to arrange the reinforcing beads 9 at the opposite ends of the shell body B on the 35 turret horn 11. This means comprises a die 47 complementary to the die portion 11', said die being in the form of a head 47 having an annular recess substantially of semi-circular form in cross section in the face thereof, as at 48. The head 47 40 is carried by a plate 49 by engaging a reduced portion of the head in an opening in said plate, as at 50, and is secured therein by a set screw 51. The plate 49 is secured to a slide 51' slidably mounted in slideways 52 in the top of the frame F to have limited reciprocatory movement toward and away 45 from a turret die 11' at station c, the slide being retained in the slideways by gibs 53. To reciprocate the slide, it is operatively connected with the pin of a crank 18' connected to the shaft 18 by connection means comprising a pair of members, one of which members having a split collar portion 54 engaged upon the crank pin and a longitudinally split tubular portion 55. The other of 50 said members has a collar portion 56 engaged upon a pin 57 mounted at the ends in and extending between walls 58 of the slide 51', and a longitudinally split tubular portion 59 extended from the collar portion 56, as shown in Figures 1 and 2. The members 54, 55 and 56, 59 are connected to 55 permit of adjustment of the slide 51' toward and away from the crank pin 18' and of the die 47 relative to turret horn and die 11, 11'. For this purpose there is provided a stud 60 having an intermediate portion 61 of increased diameter and the opposite end portions screw threaded for connection with screw threads in the split tubular portions 55, 59, whereby, as the stud is rotated in one direction, the opposite ends will be screwed into the tubular portions 55, 59; and when rotated in the opposite direction, will be screwed out of said portions, the stud being secured in adjusted position by clamping screws 62. The intermediate portion of the stud 60 is arranged for the application of an implement to rotate the same, such

as a wrench, and as shown, is arranged for the application of a pin wrench.

The operation of curling or rolling the end portions of the shell body B outwardly and inwardly upon themselves, the shell body being engaged 5 upon the turret supporting horn 11, is effected at station c. The shell body is of a length greater than the length of the horns 11, as shown at the left in Figure 2, the shell body B being initially of a length equal to the length of the turret horns 10 11 plus the amount that is rolled upon itself at the ends. As a turret horn 11 with a shell body B thereon is positioned at station c, the complementary die 47 is moved toward the die 11', and by this movement of the complementary die, the 15 edges of the shell body will first engage the wall of the semi-circular recesses in the dies 11', 47. By the continued movement of the complementary die toward the die 11' due to the conformation of said recesses the opposite end portions of the shell 20 body are rolled outwardly and inwardly upon themselves, as shown at the right of Figure 2, wherein the complementary die 47 is shown at the limit of its movement toward the die 11'.

The shell bodies are arranged with the inwardly extending nibs or protuberances 10 by means, at station d, comprising a series of indenting devices mounted on a carrier or slide 63 slidably mounted in slideways on the frame F to have reciprocatory sliding movement toward and away 25 from the turret horn 11 at station d and dispose the indenting devices about the shell body on said horn, and the provision of means to move the indenting devices toward the shell body on the horn to indent the same, maintain the indenting means in said position during the movement of the same with the carrier away from the turret horn to deliver the shell body from the horn, and operative to release the shell body from the indenting devices when they are moved 30 away from the horn. While the indenting devices may consist of any desired number, they are shown as three in number, each indenting device, as shown in Figures 3, 4, 5 and 6, comprising a block 64 each carrying or arranged 35 with a pair of indenting points 65, 65', each of said points being adjacent an end of the block and spaced apart a distance to position the indentations or nibs 10 adjacent each end and within the beads 9 at the ends of the body shell, 50 such spacing depending upon the length of the shell body. Each block is carried by and suspended between a pair of spaced arms 66 extending from one of a series of three slides 67 mounted in slideways equidistantly spaced about 55 and extending radially of a circular vertical portion 68' of the carrier 63, the slides being retained in the slideways by gibs 69. The block 64 is suspended from and between the arms 66 by a cap 67' bridging the arms and a bolt 64' 60 extended through an opening in the cap and threaded into the block. The slides 67 are urged radially outward by springs 68 to normally space the indentor points apart a distance greater than the diameter of the shell body B on the turret horn 11.

The carrier 63 with the indenting devices is reciprocated toward and away from a turret horn 11 at station d by an eccentric or cam 70 fixed on a shaft 71 journaled in a bracket 72 extended 70 upward from the frame F and operatively connected to and driven from the drive shaft 18 by a sprocket chain 73 passing around a sprocket wheel 74 on the shaft 71 and a sprocket wheel 75 on an intermediate shaft 76 journaled in bear-

ings in brackets 71 fixed upon the frame F with the lower stretch of the chain riding over an adjustable take-up roller or wheel 78. The shaft 76 is operatively connected to the shaft 18 through bevel gears, as at 79. The eccentric 70 operates between a pair of rollers 80 carried on studs fixed in and extending between a pair of plates 81 and disposed at diametrically opposite sides of the eccentric carrying shaft 71. The shaft 71 is extended through elongated openings 82 in the plates 81, the plates being mounted in slideways 83 of the brackets 72 to have reciprocatory sliding movement parallelly of the carrier 63 imparted thereto by the eccentric 70 engaging the rollers 80. The movement of the plates 81 is transmitted to the carrier 63 through a lever 84 between the brackets 72 pivotally supported at one end on a shaft 86 fixed in said brackets, the lever having a lost motion connection 85 with the plates 81. The opposite end of the lever is bifurcated and pivotally connected, as at 86', to a member 87 having a longitudinally split tubular portion 87' internally screw threaded. The carrier 63 is arranged with laterally extending and parallelly spaced members 88 between the ends of which members is pivotally connected, as at 89, a member 90 similar to the member 87 having a longitudinally split tubular portion 90' and internally screw threaded. The members 87 and 90 are adjustably connected by a stud 91 having an intermediate portion 92 of increased diameter and the portions at the opposite sides thereof of screw threaded for connection with the threaded tubular portions 87', 90', the screw threads being such, so that, as the stud is rotated in one direction, said stud 91 will be threaded into the portions 87', 90', and when rotated in the opposite direction threaded out of said portions. When the desired adjustment has been made the split portions 87', 90' are clamped to the stud by screws 93. The intermediate portion of the stud is arranged for the application of an implement, such as a wrench, and shown as arranged for the application of a pin wrench to rotate the stud. The carrier 63 is actuated in timed sequence with the rotation of the turret.

To permit of the indentor points 65, 65' pressing the nibs or protuberances laterally from the material of the shell body B on the horns 11, the horns 11 are provided with longitudinal recesses 64^a extending from adjacent the die enlargements 11' of the horns to the outer end of the horns and of a depth equal to the desired depth of the nibs or protuberances, there being three of said recesses equidistantly spaced about the horns and arranged in alinement with the indentor points 65, 65'. The recesses not only permit of the indenting of the shell body, but by extending the recesses through the outer end of the horns, permit the shell body to be withdrawn from the horns by the movement of the indenting means away from a horn.

To impart radial inward movement to the slides 67 carrying the indenting means or devices against the action of the springs 68, a disk 94 is fixed on a shaft 94', as by a set screw, the shaft being rotatably mounted at one end in the circular part 68' of the carrier 63 and at the opposite end in a part 95 extended upward from the carrier 63 and spaced rearwardly of the circular part 68' of the carrier 63. One face of the disk 94 is juxtaposed to the rear of the circular portion 68' and has a cam recess 96 in said face arranged with three equidistantly spaced cam portions 96' the wall of said recess and the cam portions 96'

simultaneously engaging rollers 97 carried on studs 97' fixed in bosses at the rear of each slide 67 extended through elongated openings 98 in the circular part 68' of the carrier 63.

The indentor-carrying slides 67 are normally urged radially outward to space the indentor points 65, 65' apart, as shown in Figure 6, a distance greater than the diameter of the shell body on a turret horn 11 stationed relative to the indentor means; and the indentors are maintained in said position during the movement of the indentor means toward the turret horn to position the indentors about the shell body on the turret horn, as shown in Figure 3. In said position, the indentor carrying slides 67 are actuated by the cam portions 96' toward the turret horn and into engagement with the shell body thereon to press portions of the material of the shell body inward to provide the nibs or protuberances 10, as shown in Figure 5. This actuation of the slides 67 is effected by the rotation of the cam 94 and travel of the high portions 96' of the cam surface relative to the rollers 97. The indentors are retained in said position during the return movement of the indentors with the carrier 63, and by the engagement of the indentor points 65, 65' in the nibs or protuberances in the shell body, said body is moved from the turret horn by said movement of the indentor means. When the shell body carried by the indentor points 65, 65' is clear of the turret horn, the cam disk 94 by the continued rotation thereof causes the high cam portions 96' to ride off from the rollers 97 and the low portions of the cam groove to ride relative to the rollers due to the action of the springs 68, as shown in Figure 6. The engagement of the rollers 97 with the low portions of the cam recess 96 will release the shell body from the indentors and permit it to pass from between the indentor points and drop through an opening 100 in the frame F.

The cam disk 94 is operatively connected with and rotated from the shaft 71 by a shaft 101 having a bevel gear connection 102 with the shaft 71. A pinion 103 on shaft 101 meshes with a gear 104 on shaft 94' connected by suitable means, shown as a screw, with the cam disk to rotate therewith. The pinion 103 is mounted on the shaft 101 to rotate with and have sliding movement on said shaft and the pinion 103 is maintained in mesh with the gear 104. For this purpose the pinion 103 is fixed on one end of a bushing 105 rotatable in a lateral extension 95' of the part 95 of the carrier 63 and secured to said extension to participate in the movement of the carrier 63 by a nut 106 threaded onto the opposite end of the bushing 105 and the side of the extension 95' opposite the pinion 103, as shown in Figure 1. To permit of sliding movement of the bushing on and rotation with the shaft 101, it is provided with a keyway for the slidable engagement of a key 107 fixed in the shaft.

The apparatus is adapted to provide beads 9 and nibs or protuberances 10 in shell bodies of different length and different diameters. For this purpose, the combined turret horns 11 and dies 11' are arranged to be interchangeably mounted in the turret head 12. The length of shell body to be acted upon is determined by the position of the face with the semi-circular recess 70 in the enlarged portion 11' of the horns 11 relative to the outer end of the horns; and to act on shell bodies of different diameters, turret-horns 11 of different diameter are provided. The indentor-point-carrying blocks 64 are also inter- 75

changeable. The indentor point 65 is always arranged at one end of the block and the indentor 65' is variably arranged on the block relative to the indentor point 65, as shown at 65" in Figure 3, showing said indentor point adjacent the indentor 65 and in position for indenting a shell body of the smallest length to be indented.

As stated, it is an object of the invention to provide means to effect vertical adjustment of the carrying frame F for the operative parts, whereby to position the turret horns 11 in line with the horn e (Figure 2) of a container body forming machine and adapt the present machine to be used in conjunction with a container-body-forming machine. To effect vertical adjustment of the carrying frame F, there is provided an auxiliary base C' mounted in slideways 108 longitudinally of the base C. The auxiliary base C' is arranged at the opposite sides and ends with laterally extending portions 109, the upper surface of which portions decline in the same direction and at the same angle, as at 110. The base or leg portions of the standards A are each provided with an undercut portion 111 bevelled or inclined to correspond with and engage the declining faces 110 of the auxiliary base C'. The auxiliary base C' is secured to the base C by bolts 112 extended through slots 113 in the auxiliary base and threaded into the base C. To facilitate adjustment of the auxiliary base C' and the frame F vertically, there is provided a lead screw 114 having threaded connection with one end of the base, or a block within the base, midway the sides thereof, and rotatably mounted in a lug 115 extended upward from the base C, and held against longitudinal movement therein by a collar 116 fixed on the screw at one side of the lug and a shoulder formed by a head 117 at the end of the screw arranged for the application of a crank to rotate the screw. To adjust the frame, securing bolts 118 are loosened when the frame F is to be adjusted upward, as well as the bolts 112 for the auxiliary base C', when the lead screw 114 is rotated to effect movement of the auxiliary base C' to the left as viewed in Figure 8, and after adjustment, the frame and auxiliary base securing bolts are manipulated to secure them to the base C. To effect vertical downward adjustment of the frame F, the lead screw 114 is rotated in the opposite direction.

To limit the movement of the carrier 63 for the indentor means toward the turret horn 11 positioned at station d relative to said means and thereby position the indentors 65, 65' to cause the nubs or protuberances to be impressed in a shell body B on said turret horn, a headed plug 63' is mounted in an opening in the portion 68' of the carrier in axial alinement with the turret horn, the head of the plug projecting from the face of the carrier and adapted to abut the end of the turret horn, as shown in Figure 3.

While I have described and illustrated one embodiment of the invention it will be obvious that various modifications may be made in the construction and arrangement of the parts and that portions of the invention may be used without others and come within the scope of the invention.

Having described my invention, I claim:

1. In apparatus for the purpose specified, a horn adapted to support a tubular sheet metal body thereon, means adapted to be disposed radially about the body on the horn operative to press portions of the material of the body laterally to form the body with inwardly extending protuberances spaced circumferentially about

and adjacent the ends of the body, one of said members being movable longitudinally toward and away from the other.

2. In apparatus for the purpose specified, a horn to support a tubular sheet metal body thereon, means reciprocatory longitudinally of the horn adapted when moved toward the horn to engage circumferentially spaced portions of the body on the horn and operative to press said engaged portions of the material of the body radially inward to form the body with spaced protuberances and move the body from the horn by the movement thereof away from the horn and release the body therefrom.

3. In apparatus for the purpose specified, a horn having recesses extending longitudinally of and radially spaced about the horn and the horn adapted to support a tubular sheet metal body thereon, a member reciprocatory longitudinally of the horn adapted when moved toward the horn to engage about the body on the horn, and means carried by said member adapted to be disposed relative to the recesses in the horn when said member is moved toward the horn and operative to press portions of the material of the body radially inward to form the body with inwardly extending protuberances circumferentially spaced from each other.

4. Apparatus as claimed in claim 3, wherein the means to form the protuberances is maintained in engagement with the protuberances formed thereby during the movement of said means with the member away from the horn and operative when the body is removed from the horn to release the body therefrom.

5. In apparatus for the purpose specified, a horn having recesses radially spaced about and extending longitudinally thereof adapted to receive and support a tubular sheet metal body thereon, a member reciprocatory toward and away from the horn adapted when moved toward the horn to engage about the same, means to actuate said member, means disposed about and carried by said member to have movement radially from the member to the horn and adapted to be disposed in alinement with the recesses in the horn when the member is moved toward the horn to co-operate with said recesses to indent and provide the body with inwardly extending protuberances adjacent opposite ends thereof during the movement of said indenting means toward the horn, and means operative when the member is moved toward the horn to actuate said indenting means toward the body on the horn, maintain said indenting means in engagement with the indentations during the movement thereof with the member away from the horn thus causing the body to move therewith from the horn and operative in said latter position to actuate the indenting means to release the body therefrom.

6. In apparatus for the purpose specified, a horn, a support for the horn mounted to have movement about an axis transverse to the axis of the horn and said horn adapted to support a tubular sheet metal body thereon, means to intermittently rotate the support with the horn and successively position the horn at different stations and adapted to receive the body thereon at one of said stations, a member at another station reciprocatory axially of and toward and away from the horn and when moved toward the horn adapted to engage about the horn, means carried by and disposed about said member to have movement radially therefrom toward the

horn and adapted to indent the body on the horn to provide the body with inwardly extending protuberances during the movement of said means toward the horn, and an actuator operative when the member carrying said means is moved toward the horn to actuate said indenting means toward the body on the horn, maintain said means in said position, thus causing the body to move therewith from the horn by 10 the movement of the carrying member therefor away from the horn, and then operative to release the body.

7. In apparatus for the purpose specified, an intermittently rotatable turret, a series of radially extending dies carried by and equidistantly spaced about the turret, a support extending concentrically from each die adapted to receive a tubular sheet metal body thereon when the dies are stationed at one position of rest of the 15 turret, a complemental die stationed relative to a turret die in another position of rest of the turret dies and operative to co-operate with a turret die to roll the opposite end portions of the body upon themselves to provide the body 20 with a bead at each end thereof, and means stationed relative to a turret die at another position of rest of the turret dies to indent and provide the body on the die with inwardly extending protuberances spaced circumferentially about and adjacent each end of the body and to remove the bodies from the supports.

8. In apparatus for the purpose specified, a rotatable turret, a series of radially extending dies carried by and equidistantly spaced about 35 the turret, means to support a tubular sheet metal body extending concentrically from the dies, means to intermittently rotate the turret to position the dies at successive stations and adapted to receive a sheet metal body on the supporting means therefor at one station, a complemental die supported at another station to have movement toward and away from a die carried by the turret and co-operate with said latter die to roll and form a bead at each end 40 of the body, and means at another station reciprocatory toward and away from a turret die and operative when moved toward said turret die to indent and provide the body with inwardly extending protuberances spaced circumferentially about and adjacent each end of the body 45 and remove the body from its support by the movement of said means away from the turret die.

9. In apparatus for the purpose specified, a rotatable turret, a series of dies equidistantly spaced about and extending radially of the 55 turret, each die having an annular recess in the face thereof, means to support a tubular sheet metal body extending concentrically of and in line with the annular recess of the die, means to intermittently rotate the turret to position the dies carried thereby at successive stations and the supporting means adapted to receive a body thereon at one of said stations, a die complemental to the dies carried by the turret supported at one of said stations to have movement toward and away from a turret die and co-operate therewith to curl and provide a bead 60 at the opposite ends of the body, and means at another station operative to eject the bodies from the supports of the turret dies.

10. In apparatus for the purpose specified, a rotatable turret, a series of dies equidistantly spaced about and extending radially of the 70 turret, each die having an annular recess in the

face thereof, means to support a tubular sheet metal body extending concentrically of and in line with the annular recess of the die, means to intermittently rotate the turret to position the dies carried thereby at successive stations and the supporting means adapted to receive a body thereon at one of said stations, a die complemental to the dies carried by the turret supported at one of said stations to have movement toward and away from a turret die and co-operate therewith to curl and provide a bead at the opposite ends of the body, and means at another station operative to indent and arrange the body on the supporting means of the turret die stationed relative thereto and provide the body with inwardly extending protuberances spaced circumferentially about and adjacent each end thereof and eject the body from the supporting means.

11. In apparatus for the purpose specified, a 21 rotatable turret, a series of supports for tubular sheet metal bodies equidistantly spaced about and extending radially of the turret, means to intermittently rotate the turret to position the supports at successive stations and the supports 26 adapted to receive a body thereon at one of said stations, and means at another station relative to which the supports are successively positioned operative to indent and arrange the body with inwardly extending protuberances spaced circumferentially about and adjacent each end of the body.

12. Apparatus as claimed in claim 11, wherein the means to indent the bodies is also operative to eject the bodies from the supports.

13. In apparatus for the purpose specified, a rotatable turret, a series of dies equidistantly spaced about and extending radially of the turret, each die having an annular recess in the face thereof, means to support a tubular sheet metal body extending concentrically of and in line with the annular recess of the die, means to intermittently rotate the turret to position the dies carried thereby at successive stations and the supporting means adapted to receive a body thereon at one of said stations, a die complemental to the dies carried by the turret supported at one of said stations to have movement toward and away from a turret die and co-operate therewith to curl and provide a bead at the opposite ends of the body, and means at another station reciprocatory toward and away from a turret die and adapted when moved toward said die to engage about the body on the support therefor of the die and in said position operative to indent the material of and provide the body with inwardly extending protuberances spaced circumferentially and between the beads at the ends of the body and eject the body from the support during the movement thereof away from the die.

14. In apparatus for the purpose specified, a rotatable turret, a series of dies equidistantly spaced about and extending radially of the turret, each die having an annular recess in the face thereof, means to support a tubular sheet metal body extending concentrically of and in line with the annular recess of the die, means to intermittently rotate the turret to position the dies carried thereby at successive stations and the supporting means adapted to receive a body thereon at one of said stations, a die complemental to the dies carried by the turret supported at one of said stations to have movement toward and away from a turret die and co-oper-

ate therewith to curl and provide a bead at the opposite ends of the body, and means at another station to indent and provide a body on the support of a turret die with inwardly extending protuberances spaced circumferentially about the body and between the beads at the ends of the body, comprising a carrier reciprocatory toward and away from the body support of a turret die, indentors spaced about said carrier to have oscillatory movement radially thereof and disposed about the body on the support of the turret die when moved toward said support with the carrier, and means operative to move the indentors to indent the material of the body on the support of the turret die, retain the indentors in said position during the movement of the carrier away from the support, and operative to release the body therefrom when the carrier is moved away from the support.

15. In apparatus for the purpose specified, an intermittently rotatable turret, a series of dies equidistantly spaced about the turret, a horn arranged concentrically of each die adapted to be successively positioned to receive a body, and a complementary die relative to which the turret horns are successively stationed and movable toward and away from and adapted to co-operate with the turret die to simultaneously curl and provide a bead at the opposite ends of the body.

20. 16. In apparatus for the purpose specified, an intermittently rotatable turret, a series of dies equidistantly spaced about the turret, each die having an annular recess, a horn arranged concentrically of each die adapted to be successively positioned to receive a body, means to intermittently rotate the turret, a die complementary to the turret dies relative to which die the turret dies are successively stationed by the intermittent rotary movement of the turret and mounted to have movement toward and away from the turret die and co-operate therewith to provide the opposite ends of the body with a rolled bead, means to reciprocate said die toward and away from the turret die stationed relative thereto, means relative to which the horns with the bodies thereon are successively stationed by the intermittent movement of the turret and mounted to have movement toward and away from said turret horn and when moved toward the turret horn operative to indent the material of the body on the horn to provide the body with inwardly extending protuberances circumferentially spaced about and adjacent each end of the body, and means to actuate said means toward and away from a turret horn, actuate the indenting means to indent the material of the body on the horn, retain the indenting means in said position during the movement thereof away from the turret horn thus

causing the body to move therewith from the horn, and then operative to release the body therefrom.

17. In apparatus as claimed in claim 10, a frame for supporting the turret, the complementary die and the indenting means, a base on which the frame is mounted to have vertical adjustment, and means to adjust the frame vertically of the base.

18. In apparatus as claimed in claim 10, a frame for supporting the turret, the complementary die and the indenting means, said supporting frame including standards having end faces inclining to the horizontal, a base upon which the frame is mounted to have vertical adjustment, a member mounted on the base to have adjustment in a horizontal plane arranged with inclined faces complementary to and for engagement with the inclined faces at the end of the frame standards, and means to adjust said member to effect vertical adjustment of the supporting frame on the base.

19. In apparatus as claimed in claim 16, a frame for supporting the die carrying turret, the complementary die, the indenting means and the actuating means, a base on which said frame is mounted to have vertical adjustment to align the horns of the turret dies to receive a body, and means operative to effect vertical adjustment of the supporting frame.

20. In apparatus for the purpose specified, a horn adapted to receive and support a tubular sheet metal body thereon, a member reciprocatory toward and away from the horn adapted when moved toward the horn to engage around the horn, means to reciprocate said member, indentor means disposed about and carried by said member to have movement radially from the member to the horn and adapted to indent and provide the body with inwardly extending protuberances adjacent opposite ends thereof during the movement of said indentor means toward the horn, means to yieldingly and normally position the indentor means in spaced relation to the horn, and means operative when the member is engaged around the horn to actuate said indentor means toward the body on the horn against the force of the yielding means into engagement with the body on the horn, maintain said indentor means in engagement with the indentations formed by the indentor means during the movement thereof with the member away from the horn thus causing the body to move therewith from the horn and operative in said latter position to actuate the indentor means under the force of the yielding means to release the body from the indentor means.

JOHN A. JOHNSON.
